United States Patent

Des. 234,358

Patented Feb. 18, 1975

234,358

FREESTANDING FIREPLACE

Paul H. Lever, Fallbrook, Calif., assignor to Fireplace Corporation of America, Walled Lake, Mich.

Filed Dec. 6, 1973, Ser. No. 422,251

Term of patent 14 years

Int. Cl. D23—03

U.S. Cl. D23—97

FIG. 1 is a perspective view of a freestanding fireplace embodying my design;

FIG. 2 is a front view thereof;

FIG. 3 is a top view thereof;

FIG. 4 is a bottom view thereof;

FIG. 5 is a left side view thereof;

FIG. 6 is a right side view thereof; and

FIG. 7 is a rear view thereof.

I claim:

The ornamental design for a freestanding fireplace, substantially as shown and described.
